TYPEWRITING MACHINE

Samuel I. Berger, Newark, N. J.

Original application September 14, 1932, Serial
No. 633,105. Divided and this application
March 1, 1934, Serial No. 713,454

2 Claims. (Cl. 197—89)

This invention relates to typewriters, and more particularly to a toy typewriter which may be manufactured at a low cost.

This application is a division of my pending application Serial #633,105, filed September 14, 1932.

It is an object of this invention to provide a typewriting machine of rugged structure and positive action which can be readily and conveniently assembled and manufactured at a low cost.

A further object is the provision in a toy typewriting machine of improved means for accurately and positively moving a carriage step by step for letter spacing purposes.

15 A further object is the provision of a simple and inexpensive carriage for a toy typewriting machine, the carriage supporting a stationary platen.

These and other advantageous objects which will later appear are accomplished by the simple and practical construction and arrangement of parts hereinafter described and exhibited in the accompanying drawings forming part hereof, and in which:

25 Fig. 1 is an elevational view in section of a typewriting machine embodying my invention,

Fig. 2 is a perspective view showing details of mechanism for moving a carriage step by step,

Fig. 3 is a perspective view of the carriage used 30 in the typewriting machine,

Fig. 4 is a bottom view of a portion of the machine showing details of the letter spacing device, and

Figs. 5, 6 and 7 are plan views showing the position assumed by said parts of the letter spacing device while moving the carriage one space,

Fig. 8 is a perspective view showing further details of the mechanism, and

Fig. 9 is a perspective view showing further details of the mechanism.

Referring to the drawings, in Fig. 1, a typewriting machine is shown to include a base 16 supporting a small casing 19 and a side support 20.

Although the drawings only show one side support 20 the complete machine includes two side supports 20 which are spaced apart, one of said supports being omitted from the drawings in order to disclose more clearly details of the internal mechanism.

50 Each side support 20 has an arcuate slot 21 in which moves a pin 23. A squared shaft 22 is also rotatably mounted in the side supports 20 (see Fig. 1).

Referring to Fig. 2 it will be seen that the pin 55 23 pivotally connects the legs of a U-shaped mem-

ber 24 to a pair of links 26 which are also pivotally connected by a pin 27 to a rockable frame 28, the latter being pivoted on a pin 29 journalled in the supports 20.

In the side walls of the frame 28 is journalled a shaft 30, having fixed thereto a typewheel 31 and a gear 37, which meshes with a gear 36. The gears 37 and 36 are at right angles to each other. The gear 36 is formed on a plate 35 which is attached by means of eyelets 35' to and moves with the plate 33. The plates 33 and 35 are rotatably mounted by means of an eyelet 34 on a cross bar 32, of the frame 28.

Pivotedly supported by shaft 30 are the legs 38 of a U-shaped member, the legs 38 having slots 39 through which pass the ends of a spring 40. Mounted rotatably on the upper end 41' of the spring is an inking roller 41 which is preferably made from an ink absorbing material and is maintained in contact with the periphery of the typewheel 31 by the action of spring 40. A rod 42 is connected to one of the legs 38 and to the side support 20.

Pivotedly supported by a pin 29 is an arm 43 having in its free end a pawl 44 which is maintained in engagement with the gear 37 by a spring 45, which is connected to the arm 43 and to the frame 28. Pivotedly connected to the pin 27 is a link 46, which is also connected to a lever 47 rotatably supported on the square shaft 22. The lever 47 has an arcuate slot 48 in which moves the bent end 49 of a rod 50. The end 49 of the rod is also connected to an arm 52 having a right angularly directed portion mounted on the squared shaft 22 to rotate therewith. The lever 47 has a similar right angularly directed portion 51 through which the shaft 22 passes freely, the lever 47 moving independently of the shaft 22. Shaft 22 has an angularly directed arm 54, to the extremity of which is attached a finger piece 55.

Referring to Fig. 4, the rod 50 is connected to one arm of the bell crank 56 which is pivotally supported by the casing 19, the other arm of the bell crank being pivotally connected to an arm 57 having a toothed extremity 58 directed at right angles to the walls 61 of casing 19 and passing through a slot 59 in the casing, the slot 59 having a greater width than the extremity 58 to enable the latter to move laterally as well as in and out of the slot.

The outward movement of extremity 58 is limited by a shoulder 60 on the arm 57, the shoulder engaging the wall 61 of casing 19. The bell crank and arm are normally maintained in the posi-

tion shown in Fig. 4, that is, with the toothed extremity 58 projecting outwardly as far as it will go, by a spring 62, which is connected to the bell crank 56 and the casing 19.

- 5 A bar 63 is positioned in the casing 19 adjacent the arm 57. The bar 63 passes through a slot 64 in the wall 61 and has a toothed extremity 65. The opposite end of the bar is enlarged at 66 and passes through a slot in the wall 67 of the casing 19, the enlarged portion 66 having a flange 68 which bears against a bowed spring 69 attached to the wall 67.

When the rod 50 is moved downwardly (see Fig. 4) the bell crank 56 is rotated clockwise to move the arm 57 laterally and downwardly, the toothed extremity 58, of course, having the same movement. Continued movement of arm 57 downwardly causes a lug 70 on the arm 57 to engage the portion 66 of bar 63 to move the latter downwardly against the action of the spring 69.

The base 16 has attached thereto a strip 71 having its side edges bent over to provide guide channels 72, in which slide the flanges 73 of a carriage 74, which has a plurality of spaced indentations 75 to receive the toothed members 58 and 65. At each end of one of the flanges 73 on the carriage are lugs 73' arranged to engage a stop 72' on one of the channels 72, to limit the movement of the carriage in both directions. In assembling the carriage and base 16, the stop 72' is bent outwardly from the path of lugs 73' until the carriage has been slid into position on the base, after which the stop 72' is bent into the path of lugs 73' to limit the movement of the carriage. Attached to the carriage is a paper guide plate 76, having attached thereto end members 77, which support an arcuate member 78 having a groove 79, in which is positioned a stationary platen 80, the latter consisting of a strip of hard rubber or similar material. The platen 80 is held in place by tabs 81 integral with the end members 77.

Struck out from the plate 76 are two spaced apart bearings 82 (only one being shown in Fig. 3), which support a shaft 83 to which is attached a roller 84, the latter projecting through an aperture 85 of plate 76 to engage a roller 86 fixed to a squared shaft 87, the latter being supported by and passing through the end members 77. The plate 76 is provided at its ends with ears 88 which also support the shaft 87.

Fixed to the end of shaft 87 is a knob 90 which frictionally engages a flat spring 92 to prevent free rotation of the shaft 87. Also mounted on the shaft 87 is a U-shaped member having a longitudinal bar 93 extending the length of the carriage and legs 94 which normally bear against the spring 92, the member having a certain amount of resiliency.

At the end of one of the flanges 73 on the carriage is a lug 73' adapted to engage a stop 72' on one of the channels 72 to limit the movement of the carriage.

65 In operation, a sheet of paper is inserted in the carriage. The plate 33, which has the letters of the alphabet, numerals and other symbols printed thereon, is rotated until the symbol desired to be typed lies between the forks of the indicator 95, which is integral with the frame 28, and the point of printing of the letters is indicated by a pointer 97 attached to the side supports 20. To make an impression of the symbol on the paper, a finger piece 25 is depressed, the finger piece being rotatably mounted on the

shaft 22, having a lug 98 which bears on the member 24 to cause the latter to move downward, which movement, through the links 26, causes counter-clockwise rotation of the frame 28, to bring the type wheel 31 in contact with the paper directly above the platen 80. The downward movement of member 24 is limited by contact with a rod 16' mounted on the side supports 20. As the frame rotates counter-clockwise the rod 42 prevents similar rotation of the U-shaped member 38, and the latter moves in a clockwise direction and causes the inking roller to pass over the type and ink the symbols before each impression. This arrangement insures uniform and positive inking at all times, it only being necessary to moisten the roller 41 with ink from time to time.

During the downward movement above described, the link 46 rotates lever 47 counter clockwise to draw the rod 50 to the right (Fig. 2) or downward (Fig. 4) to move the toothed extremity 58 from engagement with the indentations 75, and laterally. When pressure is relieved on the finger piece 25, a spring 99, connected to the member 97 and to the pin 27, returns the parts to their normal position, as shown in Fig. 1. During the return to the normal position, the toothed member 58 moves upward (Fig. 4) to engage the indentations 75 and laterally to the left to move the carriage to the left the space of one letter, (see Figs. 5 and 6). Slipping of the carriage is prevented by the toothed member 65 which ratchets over the indentations during the movement of the carriage by member 58.

When it is desired to move the carriage space by space without printing a symbol, the finger piece 55 is depressed to rotate shaft 22 to rotate arm 52 clockwise (see Fig. 8) to pull on rod 50, the lever 47 not being affected due to the lost motion connection enabled by the arcuate slot 48. Depressing of finger piece 55 will cause the toothed extremity 58 to move the carriage step by step as above described. Should it be desired to freely move the carriage without the step by step movement, the finger piece 55 is depressed as far as possible to cause the lug 70 to engage enlarged portion 66 of bar 63 to withdraw both toothed members 58 and 65 from engagement with the indentations 75 as shown in Fig. 7.

From the above description it will be seen that there has been presented a simple and inexpensive typewriting machine which is accurate and positive in operation, having a rugged structure with practically no parts to get out of order. While the machine herein described is intended primarily for use as a toy, it is obvious that the features embodied therein can effectively be applied to other typewriting machines without departing from the spirit of the invention.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In a typewriting machine, a carriage having a plurality of spaced indentations, a first toothed member and a second toothed member, resilient means urging said members into engagement with

the indentations, means to move the first member laterally and into and out of engagement with the indentations, the second member ratcheting over the indentations during said movement, and means on the first member engaging the second member to move the latter entirely out of engagement with the indentations when a predetermined force is applied to the first member.

10 2. In a typewriting machine, a carriage having a plurality of spaced indentations, a first flat member having a toothed extremity and a second flat member having a toothed extremity and an

enlarged portion, said members being movable in parallel planes, resilient means urging said members into engagement with the indentations, means to move the first member laterally into and out of engagement with the indentations, the second member ratcheting over the indentations during said movement, and a lug on the first member engaging the enlarged portion of the second member to move the latter entirely out of engagement with the indentations when a predetermined force is applied to the first member.
